Attest,

UNITED STATES PATENT OFFICE.

REINHARD E. BARTELS, OF LYNN, MASSACHUSETTS.

METHOD OF MAKING SHANK-STIFFENERS.

1,362,835.

Specification of Letters Patent. Patented Dec. 21, 1920.

Application filed December 30, 1919. Serial No. 848,309.

To all whom it may concern:

Be it known that I, REINHARD E. BARTELS, a citizen of the United States, residing at Lynn, in the county of Essex and State of Massachusetts, have invented new and useful Improvements in Methods of Making Shank-Stiffeners, of which the following is a specification.

This invention has for its object to provide a shank stiffener, especially for turn shoes which will preserve the shape of the shoe, and also serve as an arch support.

On the accompanying drawing:—

Figure 1 represents in longitudinal section, a turn shoe provided with a counter stiffener embodying the invention.

Fig. 2 shows the blank from which the stiffener is formed.

Figs. 3, 4 and 5 show the metal strip prior to its attachment to the blank.

Fig. 6 illustrates the strip as being secured to the blank.

Fig. 7 illustrates the finished shank stiffener.

Fig. 8 shows instrumentalities which may be employed for simultaneously molding the blank and the metal strip.

The body of the stiffener may be made of leather or any other semi-flexible material, such as leather board, fiber board, or the like. It is cut into blanks 10, which are approximately in shape like the rear portion of the sole of the shoe, for it is customary, in the manufacture of turn shoes, to employ a stiffener which is inserted in place after the shoe is turned and before the heel is secured in place, so that the heel-attaching nails will be clenched in the stiffener and hold it in place. The blank covers the heel seat, and extends forwardly to the "break" of the sole indicated at *a*. The forward end of the blank is secured in place by one or more fastenings *b*. The blank is skived as at 11 along its margin, and, if of leather, its grain side is uppermost. If desired, it may be skived only at its forward end.

The metal strip is indicated at 12. It consists of a piece of ductile sheet metal, which is long enough to overlie the heel, and to extend almost to the break *a*. By suitable dies, this strip is formed with a concavo-convex rib 13, which extends from one side edge to the other and which flares outwardly at its

ends to leave the strip with flat end portions 55 14, 14. In the flat ends are formed sharp or acute triangular prongs 15, 15, which may be driven into the stiffener blank and clenched if desired. For turn shoes, each strip may have two prongs at each end, but 60 for McKay shoes, a single prong may be formed at each end.

After the blank 10 and the metal strip 12 have been provided, they are assembled, in any suitable machine, in the proper relation 65 with the concave face of the rib against the face of the blank, and the prongs are driven into the blank at the smaller end thereof, so as to secure them permanently together. Then the partially formed flat shank stiffener, with the body thereof in a moistened condition if desired, is placed between molds 16, 17, and is subjected to heavy pressure so as simultaneously to mold them into the shape shown in Fig. 7, and also to force 70 the other prongs into the heel end of the blank. The blank and the strip are curved longitudinally of their length, the side edges of the metal strip being longitudinally curved, and the center of the rib, between 75 the end portions of the strip, being also curved but on a longer radius than the side edges. When the stiffener is completed, it is placed in a turn shoe, as shown in Fig. 1, with the rib resting upon the sole, between 80 the seams uniting the upper and sole. The body of the stiffener is not curved transversely of its length, but is longitudinally curved as shown, and the edges of the rib bear against the under face thereof. The 85 rib-formation of the strip prevents the body from bending or straightening out under pressure, and provides a stiff unyielding support for the arch of the foot.

It is evident that, if desired, the metal 95 strips may be galvanized or may be japanned or enameled as desired, to prevent them from rusting. After the shank stiffener is placed in the shoe, it is covered with the usual sock lining.

In simultaneously molding the blank and the metal strip into the final form, the mold may also impress in the upper face of the blank, numerals or letters to indicate the size and style of the blank. Of course, the 105 prongs may be located at any convenient point or points in the length of the strip to secure the strip to the blank.

What I claim is:

A method of making shank stiffeners, which consists in molding a metal strip with a longitudinal concavo-convex rib, assembling said strip and a semi-flexible blank, 5 with the concave face of the strip against the face of the blank, and then simulta-

neously molding the blank and the strip to curve them longitudinally of the length thereof.

10

In testimony whereof I have affixed my signature.

REINHARD E. BARTELS.
